UNITED STATES PATENT OFFICE.

MERLE J. WIGHTMAN AND HERMANN LEMP, OF HARTFORD, CONNECTICUT.

INCANDESCENT-LAMP SOCKET AND CUT-OUT.

SPECIFICATION forming part of Letters Patent No. 365,159, dated June 21, 1887.

Application filed August 27, 1886. Serial No. 211,994. (No model.)

To all whom it may concern:

Be it known that we, MERLE J. WIGHTMAN and HERMANN LEMP, citizens of the United States, residing at Hartford, in the county of 5 Hartford and State of Connecticut, have invented a new and useful Electric-Lamp Fixture for Incandescent Lighting, of which the following is a specification.

Our invention relates to the socket-piece 10 containing the circuit-controlling mechanism for the lamp and the means by which the lamp-terminals are connected to the circuit and the lamp held in place.

The object of our invention is to construct 15 an incandescent-lamp fixture which is simple in construction and which permits the lamp to be easily inserted and removed from the circuit.

It has also for its object the constructing of 20 the socket-piece out of molded insulating material, and, further, to insulate every accessible point of the fixture, for the reason that the invention herein described has been designed more particularly to be used with high-tension 25 currents.

The invention consists of a socket-piece made entirely of insulating material which is fire-proof, and that is molded in the form to be used, which socket-piece is supported by 30 the leading-in wires which are insulated, and has in its interior a non-conducting circular base-plate having contact-blocks mounted thereupon, which are connected with the leading-in wires, and in one of which is journaled 35 a key having a metallic end diagonally slotted, with a pin working in said slot and carried by the latter block. The contact-blocks also carry circuit-completing springs for establishing the circuit of the lamp and supporting it. The 40 exposed end of said key is made of insulating material, and the key is adapted to have a longitudinal movement when rotated, so as to bridge the contact-blocks and cut the lamp out of circuit. The socket-piece above is also 45 provided with screw-caps of insulating material for covering in the top of the socket-piece.

In the accompanying drawings, forming 50 part of this specification, in which like letters of reference indicate like parts, Figure 1 represents a partly sectioned side view of our fixture; Fig. 2, a partly sectioned side view at right angles to Fig. 1; and Fig. 3 shows a

transverse section of Fig. 2 through the center of the socket-piece.

In the drawings, C represents a tubular cas- 55 ing or socket-piece of molded insulating mate- rial, and has screw-caps C' and C² for cover- ing the upper part of the socket-piece and embracing the leading-in wires L L, which are suitably insulated. In the interior of this 60 socket-piece is a circular base, B, resting upon a ledge. This base has contact-blocks c c', se- cured thereto by screws, (shown in dotted lines in Fig. 2,) the said contact-pieces being pro- 65 vided with binding-screws for the leading-in wires, and having depending therefrom metal- 70 lie springs s s' of the configuration, shape, and length shown in Figs. 1 and 2. These springs are adapted to make contact with the metallic terminals of the lamp and to support the lamp. 75 The filament of the lamp is connected with two flat terminals, t t, which are insulated from each other by mica or any other insulat- 80 ing material, i, and are expanded below the point at which the globe of the lamp is sealed into a bulbous portion, b, adapted to fit in the expansion formed in the springs s s'.

The contact-blocks above referred to are 85 provided with raised portions, which have a recess in each adapted to receive the shank of the key k. The block c' is provided with a pin, p, which passes through a diagonal slot in the shank of the key. The block c' journals 90 the key in whatever position it is placed. This key is hollow and is slotted at the end, 85 which is adapted to make contact with the block c when the key is rotated, and thus short-circuit the lamp. The key, as will be 95 seen, is mounted so as to be given an axial movement toward or from the contact-block c when it is rotated by means of the pin working in the slot. The circular base B is held from rotating by a pin, o, which takes in a depression in the screw-cap C'.

The operation of the devices is as follows: 95 Supposing the key to be rotated and drawn out of contact with the contact-block c, the lamp is inserted by forcing the terminals t t between the springs s s'. This, however, does not establish the current through the lamp, 100 for the reason that it is short-circuited by the contact of the springs s' s'. When, however, the terminals t t are inserted farther, so as to separate the springs s' s', the current through

the lamp becomes established by the contact of the springs s and s' with the terminals. When the bulbous portion b of the terminals reaches the expansion in the springs s , the lamp becomes firmly secured in position, and may be readily removed from the circuit by withdrawing it. This affords ready means for inserting and removing a lamp. When the lamp is in the position shown in Fig. 1, and the key is turned as shown in Fig. 2, the current will be short-circuited at the contact-blocks c and c' , by means of the metallic end of the key, and when the key is turned in the opposite direction this short circuit will be broken and the current will flow through the lamp. It will be observed that the socket-piece C extends beyond the neck of the lamp, and that by the means we have provided the current is insulated at every accessible point, and there is no danger of a person receiving a shock in handling the lamp.

We have designed this socket-piece particularly for use with high-tension currents, and it is necessary therefore to carefully insulate every exposed portion of the fixture. The socket-piece and its screw-cap, however, could be made of metal instead of insulating material where low-tension currents are employed.

So far as we are aware, we believe ourselves to be the first to provide a socket-piece for incandescent lamps made entirely of molded insulating material, and one which is fire-proof when so molded, and also to insulate every accessible portion of an incandescent-lamp fixture. This fire-proof insulating material, which can be molded in any desired shape, is known in the trade as "bonsilate."

Having now fully described the devices of our invention, which may be varied in many ways without departing from its spirit, what we desire to claim, and secure by Letters Patent, is—

1. Circuit-controlling mechanism for an electric circuit embodying contact-blocks carrying circuit-completing springs mounted upon an insulating-base, a rotary key journaled in one of said blocks, and means for bringing the key

in contact with the other block to short-circuit the current as the key is rotated.

2. In an incandescent-lamp fixture, circuit completing and supporting mechanism consisting of contact-springs mounted upon an insulating-base and making contact at different distances from said base, those at the greatest distance therefrom forming a bulbous opening, and an incandescent lamp having flat metallic terminals insulated from each other, forming a bulbous expansion and adapted to force said springs apart and complete the circuit of the lamp, while supporting the lamp by the engagement of the bulbous portions.

3. In an incandescent-lamp fixture, circuit completing and supporting mechanism consisting of contact-springs supported by contact-blocks mounted upon an insulating-base and making contact at different distances from said base, those at the greatest distance therefrom forming a bulbous opening, an incandescent lamp having flat metallic terminals insulated from each other, forming a bulbous expansion and adapted to force said springs apart and complete the circuit of the lamp, while supporting the lamp by the engagement of the bulbous portions, and a rotary key journaled in one of said contact-blocks, having means for giving said key a motion toward and from the other block, with which it is adapted to make contact as the key is rotated.

4. In an incandescent electric-lamp fixture, the combination of the contact-springs s and s' , the former forming a bulbous opening for supporting the lamp, with an incandescent lamp having insulated terminals t and t' , provided with a bulb, b , for the purpose set forth, and operating as described.

In testimony whereof we have hereunto set our hands and seals this 27th day of July, 1886, in the presence of the two subscribing witnesses.

MERLE J. WIGHTMAN. [L. S.]
HERMANN LEMP. [L. S.]
